[57] CLAIM

The ornamental design for a chalk line marker, as shown and described.

DESCRIPTION

FIG. 1 is a front elevational view of a chalk line marker showing our new design;

FIG. 2 is a left side elevational view thereof, the right side elevational view being a mirror image;

FIG. 3 is a top plan view thereof;

FIG. 4 is a bottom plan view thereof; and,

FIG. 5 is a rear elevational view thereof.

FIG.1.

FIG.2.

FIG.3.

FIG. 4.

FIG. 5.
